WINDOW GLASS GUIDE

David C. Bailey, Amesbury, Mass.

Application March 9, 1937, Serial No. 129,836

6 Claims. (Cl. 296—44.5)

This invention relates to window glass guides, or channels which are designed for use in automobile bodies and more particularly to that type of channel which is adapted to be bent at the time of installation, to conform to the various curvatures of the window frames.

Prior to my invention channels of this type, which have been extensively used, have had notches or slots formed therein, to permit bending to conform to the various curvatures, said notches or slots being formed in the sides or in both the sides and bottom of the channel. The effect of these openings is to weaken the sides so that they are liable to be crushed in. Also, when the channel bottoms are slotted, the securing means therefor often becomes ineffective, as the heads of the fasteners are liable to pass through the slots, so that the channels are not securely held in position. Also, on account of the instability of the sides it is necessary to provide retaining means for both sides, or to have the channel set into a correspondingly deep groove.

The objects of my present invention are to provide a form of channel body or core of the type above referred to, which will be more rigid, and less liable to distortion and crushing in of the sides than the slotted types of channels, which have previously been employed, so that retaining strips need not necessarily be employed, and in which the core will be of continuous sheet metal, so that bolts or screws, which may be employed in attaching the channels to the casing will hold the same securely in position.

I accomplish these objects by providing a core of continuous sheet metal, which, while it is in flat strip form, is provided with transverse corrugations, so arranged, that after the strip has been bent into channel form and covered with cushioning material, the channel thus produced may be bent, either in plane of its sides or the plane of its bottom, to conform to various curvatures of the casings in which it is likely to be installed, thereby causing some of the corrugations to be either slightly collapsed, or expanded according to location and the strain which is placed thereon, as will be hereinafter more fully explained.

For a more complete disclosure of my invention, reference is now made to the following specification, in connection with the accompanying drawing in which:

Fig. 1 is a cross sectional view of one embodiment of my invention on a greatly enlarged scale.

Fig. 2 is a perspective view of a section of the core which is employed therein.

Fig. 3 is a side elevation with a portion of the

covering cut away, and illustrating the effect of bending the core.

Fig. 4 is a perspective view of a modified form of core.

Fig. 5 is a side elevation thereof showing the formation when bent.

Fig. 6 is a sectional view at line 6—6 of Fig. 4.

Figs. 7 and 8 are detail views of another modified form of core, shown in flat form before bending and in side elevation after bending into channel form.

While several different embodiments of my invention may be produced three primary embodiments thereof are hereinafter described, in the construction of which substantially the same process is employed, which, briefly outlined, consists in providing a strip of thin sheet metal of suitable width, in which transverse corrugations are formed, as hereinafter described, providing a covering strip of thin cloth, to the edges of which narrow strips of cushioning material, as mohair, are stitched, coating the metal strip with an adhesive and placing it in position on the covering strip and then bending the strips into channel form.

In the drawing, one of said embodiments is illustrated in Figs. 1, 2 and 3, and comprises a core *a* of thin sheet metal, in which a series of transverse corrugations *b* are formed, which extend entirely across the sides and bottom thereof from edge to edge and in perpendicular relation to the edges. While the particular form of corrugations which are employed are not essential to my invention, I have ascertained from a large number of experiments that some forms of corrugations are much preferable to others. For example, for a certain gage of metal and height of side, the semi-circular, reversely curved type shown in Figs. 2 and 3 have been found preferable to deep, sharp angled corrugations, or to corrugations which are so fine that they do not provide sufficient space to permit compression, as with either of the two latter forms the sides are liable to buckle when the channel is bent.

When the core is corrugated as shown in Fig. 2 and the channel is bent in the plane of its sides, the bottom portion between the corrugations will be bent and there will be no apparent change in the sides of the corrugations at this point, but the sides of the corrugations in the sides of the channel will be pressed together to an increasing extent from the bottom to the edges of the sides, so that they assume a tapering formation, as indicated in Fig. 3, and when the channel is bent thru approximately 90°, the sides

of the corrugations will be crowded close together at the edges of the channel.

Under some conditions it is also necessary to bend the channel in the plane of its bottom, and the construction shown in Figs. 2 and 3 is equally well adapted for bending in this manner, without causing any substantial change in cross section. The action on the corrugations, when the channel is bent in this manner, is substantially as follows.

The corrugations in the bottom of the channel will be compressed so that they taper from the side of longer radius to the side of shorter radius, and the corrugations in the side of longer radius will be expanded while those in the side of shorter radius will be compressed.

In the form of core *a'*, shown in Figs. 4, 5 and 6 the corrugations *b'* are extended across the bottom and sides and are terminated at a short distance from the edges of the strip, leaving the edge portions of the sides uncorrugated. Each edge portion is then bent about a reinforcing wire *f*, beaded edges *g* being thereby formed.

The core will be covered with cushioning material in the same manner as that already described with reference to Figs. 1 to 3.

When the channel thus produced is bent, a bending action will take place at the beaded edges and the bottom portion of the channel will be expanded or stretched, causing the corrugations to be somewhat flattened, and this action will be extended into the sides to a decreasing extent, no change in length taking place at the beaded edges, as illustrated in Fig. 5.

The formation and spacing of the corrugations in this form may also be varied from that shown without substantial effect on the bending operation and without departing from my invention.

In Figs. 7 and 8 a third form of my invention is illustrated, in which corrugations *b''*, similar to those shown in Fig. 2, are formed in each side portion and the bottom portion, but are not extended across the portions connecting the sides and bottom, Fig. 7 illustrating the formation before the strip is bent into channel form and Fig. 8 the formation after it has been thus bent. When this form of core is bent either in the plane of the sides, or of the bottom, the action on the corrugations is similar to that already described with reference to the form shown in Figs. 1, 2 and 3.

I claim:

1. A bendable window glass guide comprising

a channel shaped core of continuous flexible sheet metal having corrugations formed therein and extending transversely of the bottom and sides thereof and adapted for compression or expansion according to the stresses placed thereon when the channel is bent, and a cushion for the glass within said core.

2. A bendable window glass guide comprising a channel shaped core of continuous flexible sheet metal having corrugations formed therein extending transversely of the bottom and sides thereof and terminating at the edges of its sides, said corrugations being adapted for compression or expansion according to the stresses placed thereon when the channel is bent, and a cushion for the glass within said core.

3. A laterally and longitudinally bendable window glass guide comprising a channel shaped core of continuous flexible sheet metal having semi-circularly and reversely curved corrugations formed therein and extending transversely of the bottom and sides thereof, said corrugations being adapted for compression or expansion according to the stresses which are placed thereon when the channel is bent either in the plane of its bottom or of its sides, and a cushion for the glass within said core.

4. A window glass guide comprising a channel shaped core of continuous flexible sheet metal having corrugations formed on the bottom and sides thereof, said corrugations terminating at the corners of the channel, providing uncorrugated corner portions, and said corrugations being adapted for compression or expansion according to the stresses placed thereon when the channel is bent.

5. A window glass guide comprising a channel shaped core consisting of a continuous strip of flexible sheet metal, both edge portions of which are bent reversely to form beaded edges and having transverse corrugations formed therein extending from points closely adjacent the bead at one edge to the bead at the opposite edge.

6. A window glass guide comprising a channel shaped core consisting of a strip of flexible sheet metal having a reinforcing wire enclosed by the edge portions of its sides and having corrugations formed therein which extend transversely of the sides and bottom and terminate at said edge portions.

DAVID C. BAILEY.
